UNITED STATES PATENT OFFICE.

CHARLES M. RIDDLE, OF CLINTONVILLE, PENNSYLVANIA.

LAND-ROLLER.

SPECIFICATION forming part of Letters Patent No. 265,539, dated October 3, 1882.

Application filed July 30, 1881. Renewed March 10, 1882. (No model.)

To all whom it may concern:

Be it known that I, CHARLES M. RIDDLE, of Clintonville, Pennsylvania, have invented a new and useful Improvement in Land-Rollers, 5 of which the following is a clear, full, and exact description, reference being had to the accompanying drawings, making a part of this specification, in which—

Figure 1 is a perspective view of a land-
10 roller with my improvements attached. Fig.
2 is a side elevation of the same. Fig. 3 is a
rear view, showing one roller passing over
stones.

15 My invention relates to rollers for rolling
plowed and other ground; and it consists in
the combination of devices, as hereinafter de-
scribed and claimed, whereby the machine will
adapt itself to any uneven or irregular surface.

20 To enable others to make and use my inven-
tion, I will proceed to describe the exact man-
ner in which I have carried it out.

25 In the drawings, A represents the main
frame, in which are pivoted the large rollers
B B. The inner arms, C C, on which are jour-
naled the inner ends of the rollers, are secured
to the frame A by means of the collars a a,
which allow the arms C C a free vertical move-
ment, for a purpose hereinafter explained.
These loose arms are also secured to the outer
30 arms of the frame A by means of the metal
rod D, which bind the arms so as to hold the
rollers B B securely on their journal-bearings.

35 In order to give the rollers a vertical play,
and allow them to adjust themselves to any
irregularity of ground, the arms C C have the
free vertical play as shown in Fig. 3, and the
rollers B B are free to oscillate to meet the
requirements of the surface over which they
may have to pass. The frame A is further
40 braced by the diagonal piece E, reaching to
and joining on the front of the foot-board F.

Below the foot-board is the roller G, journaled
in the frame H, which frame is pivoted below
the center of the frame A and supports the
front of the said frame. The frame H being 45
loosely pivoted at h, the roller G has a free
lateral motion independent of the other roll-
ers, as the others are independent of each
other. It is evident that this forward truck,
50 consisting of the roller G and frame H, not
only supports the forward part of the roller-
frame A, but relieves the horses in draft and
in turning, the lateral movement of the truck
being such that it will avoid the corners of
55 the large frame and enable the team to make
a short turn.

In constructing the rollers B B of plank I
secure the staves together with dowel-pins,
and then bind the whole with an iron band, b,
set into the roller flush with its surface. I 60
first prepare the iron band of the proper size,
and then fill in the staves and secure them with
a key. The heads are put in in pieces and
spiked, leaving the heads partially open to
prevent rotting inside. When made in this 6
way the rollers will not become loose or lose
their shape.

Having thus explained my invention, what I
claim as new, and desire to secure by Letters
Patent, is—

70 A land-roller constructed as described, and
consisting of the frame A, provided with the
two vertically-swinging arms C C, secured to
the said frame by the collars a a, in combina-
tion with the rollers B B, binding-rod D, and 75
the pivoted frame H, having journaled within
it the roller G, substantially as and for the pur-
pose set forth.

CHAS. M. RIDDLE.
